LABEL HOLDER FOR FILING SYSTEMS

William L. Sparks, Hartsdale, N. Y.

Application September 23, 1942, Serial No. 459,346

2 Claims. (Cl. 129—16.8)

The object of my invention is to provide a non-metallic label holder to be detachably affixed to the guide or index cards of filing systems. Particularly it is an object to provide such a label holder from fish paper or like material which has the property of being tough, stiff, yet yielding or bendable without breaking and which may be subjected to long usage without being torn or destroyed. The label holder is constructed to be used in combination with stiff file guide cards which are provided with a series of holes at their upper edges. The label holder comprises an upperstanding label supporting body having legs which straddle the card in a cliplike manner together with bendable fastening straps which are threaded through some of the spaced holes in the card to hold the label holder in adjusted position thereon. Accordingly my invention is embodied in a label holder constructed as hereinafter described and as illustrated in the accompanying drawing in which

Fig. 1 is a face view of the label holder.

Fig. 2 is an edge view thereof looking from the left in Fig. 1.

Fig. 3 shows the label holder attached to a file index card of the type described.

The label holder is made from a strip of fish paper or like material by means of a die, not shown, which severs the holder from the strip, cuts it into shape and forms it for its purpose. Such die cutting and shaping operations are known. As shown in the drawing the label holder comprises an upper label supporting body or portion 5 of a size and shape to support whatever type label a particular filing system requires. The portion 5 has label holding lugs 7 bent up from the back 8 and it may be provided with a label enclosing bead 6. The holder is further formed with two downwardly extending side legs 9, 9 and a central leg 10 between the legs 9. The central leg has extending therefrom to each side a bendable strap 11. The legs are separated by severing cuts as at 12.

Fig. 3 illustrates a portion of a file card 14 which has a line of spaced holes 15 along the upper edge 16. The dotted lines 17 in Fig. 1 indicate the points at which the straps 11 are bent up from the holder to be inserted through two of the holes 15 in the card 14. The lines 17 indicate the points at which the straps will conveniently be bent forward of the holder and the distance between the points 17 matches the spacing of the holes so there will be no difficulty in inserting the straps.

In use the label holder is attached to the card by bending the straps up from the holder at about a right angle and passing the two straps through two holes in the card as shown at 20, 20 in Fig. 3. This action at the same time naturally places the card in front of the central leg 10 while the legs 9 are slightly lifted so as to pass in over and in front of the card. The latter is thus gripped between the legs which act like a clip. 5 Then the straps are bent towards each other and threaded through two adjacent holes as shown at 21, 21. The free ends of the straps are thus placed between the holder and the card and there are no protruding ends or edges to catch 10 the papers which are filed. The holder is detached by simply gripping the exposed portions of the straps and lifting them up. The ends of the straps then slide easily out of the holes 21. 15 Then the holder may be detached and used over again in another position on the card. The fact that the holder is made from fish paper or like material makes repeated uses and adjustment possible without injury. A label 22 is conveniently placed upon the back 8 and held by the lugs 7 as shown. The holder need not have the bead 6. It is however an advantage and presents 20 a neat appearance.

The label holder according to this invention is very inexpensive to manufacture and is a perfect 25 substitute for a metal label holder, in some respects more advantageous because repeated bending of the attaching straps does not impair the use and there are no sharp cutting edges.

I claim:

- 35 1. In combination with a file guide card having a series of spaced holes in a line along its upper edge, a label holder comprising an upper label supporting portion, separate legs extending downward from said portion straddling said 40 guide card placed edgewise between said legs to position said label holding portion above and adjacent the upper edge of said card in the plane thereof and bendable straps extending from one of said legs threaded through holes in said card 45 to affix the label holder thereto, the free ends of said bendable straps being threaded through additional holes in said card, the free ends of the straps lying between the said holder and the card.
2. In the combination according to claim 1, 50 means for positioning and securing a label on and to said label supporting portion.

WILLIAM L. SPARKS.
